UNITED STATES PATENT OFFICE.

HERBERT H. HUSTLER AND JAMES A. HESS, OF PHILADELPHIA, PENNSYLVANIA.

DESIGN FOR A COMBINED AMPLIFYING CABINET AND AQUARIUM.

Application filed October 25, 1927. Serial No. 23,881. Term of patent 14 years.

To all whom it may concern:

Be it known that we, HERBERT H. HUSTLER and JAMES A. HESS, citizens of the United States, residing at Philadelphia, in the county of Philadelphia and State of Pennsylvania, have invented a new, original, and ornamental Design for a Combined Amplifying Cabinet and Aquarium, of which the following is a specification, reference being had the accompanying drawing forming a part thereof.

Figure 1 is a front view of a combined amplifying cabinet and aquarium, showing our new design.

Figure 2 is a side view of the same which is identical with the rear.

We claim:

The ornamental design for a combined amplifying cabinet and aquarium, as shown.

HERBERT H. HUSTLER.
JAMES A. HESS.
